Inventor

George A. Rausch, Jr.

UNITED STATES PATENT OFFICE.

GEORGE A. RAUSCH, JR., OF MARYSVILLE, OHIO, ASSIGNOR TO THE MARYSVILLE CABINET COMPANY, OF MARYSVILLE, OHIO.

COPY-HOLDER.

No. 893,593.

Specification of Letters Patent.

Patented July 14, 1908.

Application filed September 30, 1907. Serial No. 395,211.

To all whom it may concern:

Be it known that I, GEORGE A. RAUSCH, Jr., a citizen of the United States, residing at Marysville, in the county of Union and State of Ohio, have invented a new and useful Improvement in Copy-Holders, of which the following is a specification.

This invention relates to copy holders especially adapted to be used in connection with a typewriter for supporting the note-book or a single sheet in front of the operator so that it can be readily read by the operator, the object being to provide a holder which is exceedingly simple and cheap in construction and one which can be readily attached to a typewriter table or cabinet.

Another object of my invention is to provide very novel means for holding the leaf of the tablet back after the operator is through with the same, so that it will not fall down over the sheet in view.

With these objects in view, the invention consists in the novel features of construction, combination and arrangement of parts, hereinafter fully described and pointed out in the claims.

In the drawing forming a part of this specification:—Figure 1 is a perspective view of my improved holder detached, showing a note book arranged therein in dotted lines. Fig. 2 is a rear view of my improved holder, showing it attached to a typewriter table or desk, the copy-book being arranged therein in dotted lines.

Referring to the drawing A and B indicate a pair of stout wires, spaced apart by a plate C, the side edges of which are bent back upon themselves over the wires A and B, and soldered, so as to hold the wires in a rigid position. The lower ends of the wires are off-set as shown at A', B', the depending ends of which are adapted to fit in sockets formed in a typewriter-table or desk D, to the rear of the typewriter. The upper ends of the wires are bent outwardly, then inwardly toward each other forming spring-arms A² B², which are bent at right-angles as shown at A³ B³, and crossed, the end of the wire A³ is bent to form a loop A⁴, the free end of which is bent first upwardly, and then downwardly as shown at A⁵ adapted

to engage the folded leaf of a note-book when arranged therein. The end of the wire B³ is bent forwardly and inwardly, the extreme end of which is bent upwardly forming a hook B⁴ which is adapted to engage the other side of the note-book, and it will be seen that when a note book is placed between the same, the spring arms will securely hold the book tightly, so that it will lay flat upon the arm, whereby it will be clearly in view of the operator at all times, and as the pages are copied and turned back, they will be securely held in that position. 65

Having thus fully described my invention, what I claim as new and desire to secure by Letters Patent is:—

1. A copy-holder comprising a pair of wires and means for spacing said wires apart, 70 the upper ends of said wires being crossed and provided with supporting members, for the purpose set forth.

2. A copy-holder comprising a pair of wires and means for spacing said wires apart, 75 the upper ends of said wires being bent at right-angles and crossed having their ends bent to form supporting members adapted to engage the book.

3. A copy-holder comprising a pair of 80 wires and a plate for spacing said wires apart, the lower ends of said wires being angled adapted to fit in sockets, the upper ends of said wires being crossed, one of which is bent to form a loop, and the other a hook for engaging with the sides of a note-book, the end of the loop being bent inwardly adapted to engage the folded sheet of the note-book, for the purpose set forth. 85

4. A copy-holder comprising a pair of 90 arms and a plate for securing said arms together, the ends of said arms being bent at right angles and crossed, one of the arms being bent to form a hook, the end of which is bent upwardly, and the other arm being 95 bent to form a loop, the end of which is bent inwardly and downwardly forming a gripping member adapted to engage the folded leaves of the note-book, for the purpose set forth.

GEO. A. RAUSCH, JR.
